[57] CLAIM

The ornamental design for a cabinet for an autosampler, as shown and described.

DESCRIPTION

FIG. 1 is a perspective view of a cabinet for an autosampler embodying our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showings of a robot arm, and sample carrying trays are for illustrative purposes only and form no part of the claimed design.
